UNITED STATES PATENT OFFICE.

WILLIAM JOSEPH HOSCEIT, OF CHICAGO, ILLINOIS, ASSIGNOR TO NATIONAL DUMP CAR COMPANY, OF CHICAGO, ILLINOIS, A CORPORATION OF MAINE.

RAILWAY-CAR COVER.

1,363,195.

Specification of Letters Patent. Patented Dec. 21, 1920.

Application filed July 27, 1917. Serial No. 183,059.

To all whom it may concern:

Be it known that I, WILLIAM JOSEPH HOSCEIT, a citizen of the United States, and resident of Chicago, in the county of Cook 5 and State of Illinois, have invented certain new and useful Improvements in Railway-Car Covers, of which the following is a specification.

This invention relates to railway cars, and 10 more particularly to covers therefor.

One of the objects of my invention is to make a car convertible to carry various kinds of merchandise.

Another object is to cover an open freight 15 car in a novel manner.

Another object is to secure the cover in a novel manner.

And a further object is to provide a cover and secure the same to a car in a manner 20 to meet the various requirements for successful commercial operation.

These and other objects are accomplished by providing a cover for railway cars including a frame having relatively adjustable sections, and closure means carried by 25 the frame.

The invention is illustrated on the accompanying sheets of drawings, in which,

Figure 1 is a top plan view of my novel 30 car cover;

Fig. 2 is a fragmentary sectional view of the same taken along the plane of line 2—2 of Fig. 1;

Fig. 3 is a fragmentary sectional view of 35 the same taken in the plane of line 3—3 of Fig. 2;

Fig. 4 is a detail sectional view showing the method of securing the flexible portion of the cover in operative position;

Fig. 5 is a sectional view of the same taken 40 in the plane of line 5—5 of Fig. 4;

Fig. 6 is a detail plan view of the same, and

Fig. 7 is a fragmentary sectional view 45 showing a modification of the securing means.

The various novel features of my invention will be apparent from the following description and drawings and will be particularly pointed out in the appended claims.

Freight cars are in great demand these 50 days, this being true of all types of freight cars. My invention has particularly to do with general service freight cars which have no top. These cars are used primarily for carrying coal, sand, gravel or in short any

articles which are not affected by the weather. In these days of car shortage it is found imperative to use these open top cars for shipping articles which would be affected by the weather, if the articles are to be 60 moved within a reasonable time.

To make possible the use of these open top cars for the purpose of carrying grain and other material which is affected by the weather, I have provided a novel removable 65 and adjustable cover for the same thereby making them convertible for the purpose indicated.

The car which is illustrated herein is provided with side walls 10, end walls 11, and 70 a floor 12. My cover, which is removably and adjustably secured to the car to make the same a closed car, includes a plurality of carlines 13, which extend transversely with respect to the car and have notched portions 14, which fit over angle bars 15^a carried on the upper edges of the car sides and ends. These carlines 13 are connected longitudinally by ridge pieces 15 and 16, which have hooked ends passing through openings 13^a 80 in the carlines whereby the ridge pieces are removably locked to the carlines. The ridge pieces 16 include relatively adjustable sections 17 and 18, whereby the sections between the carlines may be made larger or 85 smaller in accordance with demands.

As shown in Fig. 1 the car cover is adjusted to fit the regulation 40 ft. gondola car. By means of the adjustable ridge pieces the frame of the car top may be adjusted by means of the rigid members 17 and 18, so that the cover may fit 36 and 34 ft. cars. By placing the adjustable members 17 and 18 between every two carlines, the cover can be contracted even a greater 95 amount. The adjustable members are secured in any adjusted position by suitable bolts and nuts 19. When the frame of the cover is properly adjusted over the top of the car, the flexible portion of the cover 100 may be stretched or placed over the frame of the cover and secured in position. This flexible portion or member 20 of the cover is preferably a fabric such as canvas. The outer sides of the canvas member 20 are 105 provided with loops 21 for the reception of pieces of wood 22 which may be of any desired dimensions, said pieces of wood acting as anchors for stretching the fabric over the frame work and also for facilitat- 110

ing securing the fabric in operative position. Auxiliary strips of fabric 23 are also provided at either side of the car, said strips acting in conjunction with the main piece 5 of fabric 20 to prevent water from being driven into the car at the top portions thereof. Each of the strips 23 has a plurality of loop portions 24 and 25 which receive pieces of wood 26 and 27, respectively, of 10 suitable dimensions. The pieces of wood or liners 26 rest upon the lateral inclined portions 28 of the carlines and the liner 22 of the main piece of fabric rests on top of the liner 26. These parts are held in a locked 15 position, preferably as shown in Fig. 5, by hinges 29, one member 30 of each of which extends upwardly and sidewardly over the liner 22, and has an upstanding portion 31 having an opening 32 through which a 20 clamping rod 33 passes.

By referring to Figs. 1 and 3, it will be noted that the clamping rod 33 is preferably made up of three sections, 34, 35 and 36, the two outer sections 34 and 36 being linked 25 with the middle section 35, the free ends of the outer sections passing through the openings 32 of the upstanding portions 31 of the hinge members 30, nuts 37 being secured to the threaded ends of the rod sections 34 and 36 to clamp the main part of the cover in its normal stretched and weather protecting position. It will be noted that the middle sections 35 of the clamping rods pass through eye-members 38 carried by cross supporting pieces 39 located over the carlines and upon which the walk planks 40 are mounted. The other member 41 of each of the hinges extends downwardly and has a laterally extending 40 portion which fits under the liner 27, which is pressed upwardly into engagement with the under side of the laterally extending flange of the side angle members 15^a. Each of the hinge members 41 is held in a securing 45 position by U-bolts 42 which pass through slots 43 in the carlines 13, and the ends of which U-bolts extend outwardly through openings in the ears 43^a of the hinge member 41, and are tightened by nuts 44 to lock the hinge members in place to hold the flexible cover portions in a weather 50 protecting position. At the same time by means of this locking arrangement the frame work of the top is made rigid. The 55 ends of the fabric or flexible covering 20 pass over the end carlines 13 which are preferably covered by canvas 45 or the like to prevent wear of the main covering 20. The ends of the canvas are provided with loop 60 portions 46 which receive liners 47 by means of which the ends of the fabric may be held and secured to the ends of the car in any suitable manner.

By means of this cover it is apparent that

grain or other materials which may be 65 affected by adverse weather conditions, may be safely carried without any damage being occasioned.

In Fig. 7 I have shown a modification of the securing means for the cover in which 70 I substitute for the hinges a bracket member 48, the lower end of which passes under the liner 49 and the upper portion of which is bent laterally and presses down upon the liner 50 for securing the parts in position. 75 It will be noted that the bracket 48 is held in a position for locking the parts together solely by the U-bolts 51, the cross tie rods shown in the other figures being dispensed with.

By means of this adjustable car cover, car utility is greatly increased, said cover being made to fit the regulation 40 ft. gondola. It can also be easily adjusted, as hereinabove stated, to fit 36 and 34 ft. cars. When 85 cars loaded with coal are sent to the grain belt they can be returned to the grain terminal under load, with the grain lading in perfect safety, protected by the weather proof fabric placed over the carlines as 90 shown. The return of this adjustable cover from any grain terminal to the grain belt can be made easy by grouping the wooden parts together in three or four bundles; the fabric top can be rolled up in one bundle 95 and the hinges, brackets, bolts, etc., can be put into a small sack. The dismantled cover occupies very little space and can be knocked down or assembled in a short length of time.

It is apparent that there may be various modifications of the invention herein particularly shown and described, and it is my intention to cover all such modifications which do not involve a departure from the 105 spirit and scope of the invention as set forth in the following claims.

I claim:

1. A cover for railway cars, including centrally arranged frame members having 110 relatively adjustable sections for varying the length of the cover, and a trainman's walk supported by said members.
2. A cover for railway cars, including frame members having relatively adjustable 115 sections for varying the length of the cover, a trainman's walk supported by said members, and weather protecting means mounted over the frame members and under the walk.
3. A cover for railway cars, including frame members having relatively adjustable sections for varying the length of the car, a trainman's walk supported by said members, and a flexible water protecting member mounted over said frame members.
4. A cover for railway cars, including a plurality of spaced members, relatively ad-

80

100

justable members connecting said spaced members, and a trainman's walk supported by said members.

5. A cover for railway cars, including carlines having openings therein, a flexible member mounted over said carlines, a securing member, and locking means passing through said openings and coöoperating with said securing means to lock the flexible member on said carlines.

6. In combination, a car, a cover therefor including spaced members, a flexible member mounted thereover, hinge members mounted on opposite sides of said car and operatively connected to said flexible member, means for securing the flexible member to said spaced members, and members connecting said hinge members on opposite sides of said car.

20 7. In combination, a car, a cover therefor including carlines with openings therein, flexible means mounted over said carlines, hinge members operatively connected with said car and with said flexible means, lock-

ing means passing through the openings in 25 said carlines and securing the hinge members in a locking position, and transversely extending members connecting the hinges on opposite sides of said car.

8. A cover for railway cars, including 30 spaced members, means for connecting the same, weather protecting means covering said spaced members, a walk extending over said spaced members, and means supported by said walk for holding the covering means 35 to said spaced members.

9. A cover for railway cars, including spaced members, means for adjustably connecting said spaced members to vary the distance therebetween, a flexible weather 40 protective member extending over said spaced members, and means extending transversely of the cover for retaining the flexible member on said spaced members.

Signed at Chicago, State of Illinois, this 45
23rd day of July, A. D. 1917.

WILLIAM JOSEPH HOSCEIT.
